UNITED STATES PATENT OFFICE.

JOHN B. HARLOW, OF UPPER MONTCLAIR, NEW JERSEY, ASSIGNOR TO WESTERN ELECTRIC COMPANY, INCORPORATED, OF NEW YORK, N. Y., A CORPORATION OF NEW YORK.

SELECTIVE SIGNALING SYSTEM.

1,291,861.

Specification of Letters Patent. Patented Jan. 21, 1919.

Application filed May 25, 1917. Serial No. 170,821.

To all whom it may concern:

Be it known that I, JOHN B. HARLOW, a citizen of the United States, residing at Upper Montclair, in the county of Essex and State of New Jersey, have invented certain new and useful Improvements in Selective Signaling Systems, of which the following is a full, clear, concise, and exact description.

10 This invention relates to selectively controlled signaling systems, and more particularly to systems in which signals operated over one energizing circuit are controlled in their operation over an auxiliary signaling circuit.

15 The object of this invention in general is to provide means whereby all of the signals of a system may be moved from a safety indicating position into a danger indicating position in case of any failure of the auxiliary circuit over which the operation of said signals is controlled.

20 In accordance with the general features of this invention the circuit for each signal is controlled at two points, one point being controlled by the selective apparatus in its normal operation, the other point being controlled by means of a retarded circuit controlling device which is automatically controlled over the auxiliary circuit independently of the selectively operated apparatus. In the specific embodiment of the invention shown there is provided an electromagnet individual to each signal, which electro-25 magnet is intermittently energized from the sending station of the signal controlling circuit and which is provided with retarding means for preventing the armature reaching a position to control its break 30 point until after the expiration of a time period longer in duration than the period between two successive closures of the auxiliary circuit.

In the drawings:

35 Figure 1 is a diagram of apparatus and connections illustrating one form of the invention; and Fig. 2 is a detail view of a retarding mechanism of a controlling magnet which may be employed in practising 40 this invention.

45 As shown in Fig. 1, 5 and 6 designate the rails of a railway track by the side of which and at separated points are located semaphore signals 7 and 8. Each of the signals

7 and 8 is included in a normally closed 55 circuit, each circuit including two normally closed contacts 9 and 10, and a source of current 11. While a source of current 11 is shown for each of the signals 7 and 8, it is obvious that a single source would 60 suffice.

Each of the normally closed contacts 9 of the energizing circuits is controlled directly by a rotatable switch 13, which, in turn, is controlled by a selectively operated circuit 65 controlling device 14, located at what may be termed for convenience stations B and C, and controlled over wires 15 and 16 from a main or sending station A. Each of the selectively operated devices is of a well-70 known form, and comprises generally a step-by-step circuit closing element 17, adapted to close with a stationary contact member 18. The operation of the step-by-75 step element is under control of a quick-acting stepping magnet 20 and a slow release holding magnet 21, both of which are connected in series with each other in a bridge of the circuit including the wires 15 and 16. The holding magnet 21, when energized, controls a holding pawl 22, which serves to hold the step-by-step element 17 in the position to which it is advanced by a pawl 23 operated by the stepping magnet 20. The selectively operated devices 14, 14 80 operate in response to current impulses from the main or sending station A, at which there is located an impulse transmitting device 25 adapted to intermittently close the circuit of an impulse relay 26, 90 which connects a source of current 27 with the line wires 15 and 16. The selectively operated devices at the stations B and C are each adjusted to close circuit with the stationary contact member 18 in response 95 to a different number of impulses from station A. The engagement of the circuit closing element 17, of either of the selectively controlled devices, with its co-operating stationary contact member 18 will complete a 100 circuit for a magnet 28 associated therewith, the energization of said magnet causing a one step movement of the rotatable switch 13 of that station, which will open the contact 9 and cause the signal associated therewith to move to a danger indicating position. The contact 9 may be again closed to restore the signal to its energized or safety

indicating position by a subsequent operation of the same selector, which was operated to cause it to move to a danger indicating position, the subsequent operation of the selector again causing the operation of the magnet 28 to move the switch 13 another step and close the circuit at the contact 9. The opening of the contact 10 of each of the signals is controlled through the agency of an electromagnet 30 having an armature 31 to which is attached a mechanical retarding means. This retarding means comprises, in general, a fan governor 32 connected through a chain of gears comprising a pinion 33, a gear 34, a pinion 35, and a gear 36, and a pawl 37 with the armature 31. The pawl 37 engages the teeth of the gear 36 to rotate it in one direction in response to the pull of a spring 38 and the force of gravity acting upon said armature. In the movement of the armature 31, in response to a current impulse through the winding of the electromagnet 30, the pawl 37 will ride over the teeth of the gear wheel 36. An arm 40, carried by armature 31, is adapted, after the armature 31 has traveled a certain distance, to engage and open the contact 10. A continuously moving circuit closing device 45, located at the main or sending station A, is adapted to intermittently close a circuit for the impulse relay 26, which will operate the stepping magnet 20 of the selector at station B to close a circuit for the magnet 30 at that station, or a relay 46 at the station C for closing an energizing circuit for the magnet 30 at that station. The circuit for the magnet 30 at station B will be from the source of current 11, over conductor 47, conductor 48, through contact 49 controlled by the armature of the stepping magnet 20, over conductor 50 and through the winding of magnet 30 to ground. The circuit of the magnet 30 at station C will be from the source 11 at that station, over conductor 51, through contact 52 of the relay 46, over conductor 53 and through the winding of electromagnet 30 at that station to ground. The length of time elapsing between successive closures of the line circuit by the operation of the circuit closing device 45 will be less than the time required for the armature 31 to move from its energized position to a position where it will open the contact 10, thereby insuring that the signals 7 and 8 will be maintained in a safety indicating position unless operated in response to the selectively operated devices or unless there is some trouble on the circuit including the line wires 15 and 16, which will prevent the transmission of the impulses in response to the operation of the circuit closer 45.

A stop member 60 is provided for limiting the movement of the armature 31 in response to current impulses through the magnet 30, thereby preventing said armature being moved more than a definite distance in re-

sponse to a series of rapidly recurring impulses, which are sent in operating the selectively operated devices.

A relay 61 included in circuit with the impulse transmitting device 25 is energized during the operation of the device 25 to disable the circuit of the continuously rotating circuit closing device 45 during the operation of the selectively operated devices. 70

What is claimed is:

1. In a selectively controlled signaling system for railways, a plurality of electrically controlled signals normally standing in a safety position, a circuit over which said signals are controlled, selectively operated 80 circuit controlling devices for controlling movement of any of said signals from a safety to a danger position, an auxiliary circuit over which said selective circuit controlling devices are operated, and means 85 controlled over said auxiliary circuit for causing the movement of all of said signals from safety to danger position in case of failure of said auxiliary circuit. 75

2. In a selectively controlled signaling system for railways, a plurality of electrically controlled signals, a normally closed energizing circuit for maintaining said signals in a safety indicating position, selectively operated circuit controlling devices for controlling the operation of said signals, an auxiliary circuit over which the selectively operated circuit controlling devices are operated and means associated with each of said signals and controlled over said auxiliary 90 circuit for opening the energizing circuit of said signals in case of failure of said auxiliary circuit. 95

3. In a selectively controlled signaling system for railways, a plurality of electrically controlled signals, a normally closed energizing circuit for maintaining said signals in a safety indicating position, two normally closed break points in the circuit of each of said signals, selectively controlled apparatus for opening one of said break points, an auxiliary circuit over which said selectively controlled apparatus is operated, retarded operating means associated with each of said signals for controlling the other of said break points, and means controlled over said auxiliary circuit for maintaining said second break point closed in the normal condition of said auxiliary circuit. 100 110

4. In a selectively controlled signaling system, a plurality of electrically controlled signals, a normally closed energizing circuit for maintaining said signals in a safety indicating position, two sets of normally closed contacts in the circuit of each of said signals, selectively operated devices for controlling the opening and closure of one of said sets of contacts, an auxiliary circuit over which said selective devices are controlled, an electromagnet associated with each of said sig- 115 120 125 130

nals, an armature for said electromagnet adapted to open the second set of normally closed contacts in the circuit of a signal, retarding means associated with said armature for preventing its opening said second set of contacts until after the expiration of a predetermined time, and means for energizing said electromagnet at regular time intervals by impulses over said auxiliary circuit, the period of time between said impulses being 10 less than the time required by said retarded armature to move to a position to open said second set of contacts.

In witness whereof, I hereunto subscribe my name this 23rd day of May, A. D., 1917. 15

JOHN B. HARLOW.
